CLOSE-QUARTER PEEN

William P. Goede, Baltimore, Md., assignor to
 The Glenn L. Martin Company, Middle River,
 Md., a corporation of Maryland

Application May 17, 1949, Serial No. 93,705

4 Claims. (Cl. 78—46)

1

My invention relates to an improved riveting tool and more particularly to a rivet gun peen adapter for driving rivets under close-quarter conditions wherein the rivet is angularly displaced from the axial center line of the riveting gun.

In riveting sheet metal, it is very important that the riveting force be applied axially of the rivet; otherwise, the rivet head may be improperly or insufficiently formed or the rivet misaligned relative to the rivet holes so as to cause costly reworking or replacement of an assembly. Most of such trouble arises in the driving of rivets located within a channel member or behind other structural members blocked off from an aligned approach. Other hard-to-get-at places are where metal sheets are riveted to relatively narrow separators which allow insufficient head-space for operation of a rivet gun in the usual manner. In these cases, it is practically impossible to apply riveting force axially of the rivet. Various unsuccessful attempts have been made prior to this time to solve this problem either by the use of an offset peen which has proved inefficient in its delivery of rivet force and has limited application, or by flexible force delivering devices which are extremely costly, inefficient, and usually require special gun equipment for use therewith.

The present invention comprises a rivet gun attachment having a relatively light-weight riveting block pivotally mounted at the end of a bracket arranged as an offset extension adapted for slipped-on mounting over the nose of a conventional pneumatic-type rivet gun so as to effect aligned engagement with an angularly displaced rivet.

It is among the objects of this invention to provide a simple rugged rivet peen for use with a conventional rivet gun for applying rivet force to a rivet under close-quarter conditions and at hard-to-get-at locations.

Another object is to provide a riveting device for use with an air hammer for directing force angularly relative to the center line of said hammer.

A still further object is to provide a device for swiveled mounting on a pneumatic-type rivet gun.

Other objects of this invention will become apparent from the following description when taken in conjunction with the drawing in which like numerals refer to like parts in different views.

In the drawing:

Figure 1 is a side elevation of the tool of this

2

invention shown in operating position mounted on a conventional rivet gun.

Figure 2 is an end view of the tool taken on line 2—2 of Figure 1.

Figure 3 is a sectional view of the riveting block showing mounting of the balled end of the peen member therein.

Figure 4 is a cross-sectional view of the riveting block taken on line 4—4 of Figure 3.

10 Referring in detail to the drawing, Figure 1 illustrates the close-quarter rivet gun peen of this invention mounted on the nose 10 of a conventional air-operated percussion-type rivet gun. The nose 10, or cylindrical housing, of the gun is provided with an axial bore 11 of conventional proportions adapted to receive the shank 12 of a peen member 13 for delivering riveting force outwardly of the gun. The gun end 14 of the peen member 13 is formed with a flat hammer surface adapted to receive rivet driving force from the gun hammer member 15 positioned inside the gun for reciprocated movement under air pressure. The other or forward end 16 of the peen member 13 is formed with a spherical surface. The depth to which the peen 13 can be inserted in the gun nose 10 is governed by the conventional type of collar 17 customarily formed around the outer periphery of a peen shank adapted for insertion in a rivet gun.

30 The main body of the instant tool is formed as an angular bracket 18 having a portion thereof arranged as an integrally formed collar 19 placed at right angles to the midsection portion 31 and adapted for a loose slide fit around the gun nose 10. In order to provide for free and angular movement of the gun nose 10 within the collar 19, its inner peripheral surface 32 is preferably formed with rounded shoulders as shown in Figures 1 and 2. The midsection 31 of the bracket

40 18 is normally positioned parallel to the axis of the gun with the end opposite from collar 19 being formed as a slotted end 20 normally positioned on a plane with but spaced from the ball-like or spherical surfaced forward end 16 of the peen member 13. The slotted end 20 of the bracket 18 is formed to receive one end 30 of a riveting member, or block 22 with said one end of the riveting block being apertured for pivoted mounting about a pin or bolt 21 carried by said slotted bracket

45 end with the opposite end 24 of the block being positioned for engagement with the balled peen member 16. The balled peen member 16 is fitted for socketed engagement within the riveting block 22 at a point spaced from the pivot point 21 in a socket 23 formed in the riveting block as a

closed-ended groove. The socket 23 of the riveting block 22 (see Figures 3 and 4) is arranged as a round ended bore, or groove, extending inwardly from the pivoted end 30. The top of the groove is formed as inwardly extending lips 31 proportioned to secure the balled peen member 16 against upward movement but allow for radial movement relative to the block. Originally the balled end 16 is inserted into the groove, or socket 23, from its open end with the stem portion of the peen member 13 extending upwardly out of the block 22 between the lips 31. The block is then mounted in the end 20 of the bracket 18 with the socket 23 closed off by the pivot bolt 21.

In all normal riveting positions, the peen member 13 is driven against the solid end 24 of the riveting block 22 by the percussion movement of the rivet hammer 15. However, under certain conditions, there is a tendency of the peen member 13 to vibrate and chatter if allowed free play. In those instances where such vibration proves undesirable, I have found it desirable to place a coiled spring 25 between the balled peen end 16 and the pivot bolt 21 so as to hold the balled peen end securely socketed against the block end 24 under the urge of said spring.

The bottom of the riveting block 22 is formed with a plane surface or rivet engaging face 26 suitable for riveting engagement with either the shank end of a rivet to form a number two head thereon as illustrated in Figure 1 with the flush rivet 27 inserted through a metal sheet 29 and a channel 28 and held in place against the sheet by a bucking bar 33, or for conventional engagement with the formed head of a rivet under the same or similar conditions. In either case, the riveting block 22 is adapted for positioning normal to the axis of the rivet so as to deliver riveting force in alignment with the rivet even though the air gun is not aligned with said rivet axis. The clapper-like mounting of the riveting block 22 is such as to allow the percussion force developed in the conveying member 13 to be delivered to the rivet substantially as if the rivet gun were aligned with the rivet. In this manner, riveting under an overhanging channel, or other hard-to-get-at place, is readily accomplished by placing the riveting block 22 normal to the rivet with the gun angularly displaced therefrom as provided for by the cooperative arrangement of the bracket 18, peen member 16, and riveting block 22.

The inner peripheral area 32 of collar 19 is sufficiently greater in diameter than the gun housing 10, as best illustrated in Figure 2, so as to allow for considerable radial displacement between these parts which in turn allows for a wide range of movement of the gun nose 10 toward and away from the bracket midsection 31. This loose-fitting arrangement between the bracket collar 19 and the gun nose 10 enables the gun to be swung over a relatively wide range of approach relative to the axis of the rivet work piece. The cooperative ball and socket and pivot mounting of the rivet block 22 relative to the peen member 13 and bracket 18 provided for sufficient variable angular displacement of the tool to enable a workman to work "up under" or "over" obstructions of varying dimensions as working conditions necessitate.

In the operation of my close-quarter peen, or adapter, to apply riveting force to a rivet in a hard-to-get-at location where the rivet gun cannot be aligned with the rivet the first step is to withdraw the conventional type of peen

from the gun. The adapter of this invention having been previously assembled with the balled peen 16 socketed in the riveting block 22 pivoted to the bracket 18 is inserted over the gun nose 10 with collar 19 in encircled position relative thereto and the shank end 12 of the peen member 13 positioned in the bore 11 of the gun. The bracket 18 is then grasped by the operator in one hand with the other hand holding the gun by the piston grip portion (not shown). Engagement of the block 22 with the rivet 27 within the channel 28 is accomplished by pushing its end 24 forwardly relative to the gun by pulling back on the bracket 18 while at the same time pushing the gun nose 10 forwardly within the collar 19. Application of air under pressure will result in development of hammer action of member 15 which is conveyed to the riveting block 22 by the peen member 13. Retraction of the gun nose 10 relative to the collar 19 may be desired to reverse the angle of approach as determined by the type of obstruction to be circumnavigated.

Assembly of the adapter with a conventional rivet gun and its operation is easily and quickly accomplished by the average operator as part of his regular riveting routine for there are no tools required to make the change or any special riveting technique to learn.

While I have described my invention in detail in its preferred embodiment, it will be obvious to those skilled in the art after understanding my invention, that various changes, alterations, modifications, and substitutions can be made therein without departing from the spirit and scope of the claims.

I claim as my invention:

1. A tool for operation with a portable percussion-type rivet gun having an extended housing and a hammer member comprising a percussion member having a shank end adapted for insertion within the gun housing to engage the gun hammer, said percussion member being formed with a spherical free end, a bracket adapted for slidable mounting on the gun housing and having an end portion spaced from the spherical end of the percussion member, a riveting block having one end hinged to the end of the bracket with the other end in pivotal engagement with the free end of the percussion member and adapted to effect delivery of force from the rivet gun.

2. A rivet peening tool for use with a rivet gun having a cylindrical housing and a bore comprising a ball-ended peen adapted for insertion in said gun bore, a riveting member having a plane rivet engaging surface and a semispherical socket spaced inwardly therefrom for mutual cooperation with said ball of the peen to provide for movement therebetween, said riveting member being provided with a pivot point spaced from the socket, a securing means in engagement with the riveting member at said pivot point comprised of a bracket member including a sleeve adapted to loosely surround said housing for movement longitudinally of the gun to angularly displace said riveting member relative to the axis of the peen and thereby engage at right angles a rivet angularly displaced from the axis of said peen.

3. A rivet peening tool for attachment to a riveting means having a bore mounted hammer comprising a peen member having one end adapted for insertion in the gun bore to engage with said hammer, the other end of said peen being formed

spherical, a rivet engaging member having a groove extending from one end thereof terminating as a pocket adjacent the opposite end to form a socket for said spherical end of the peen, a pivot point formed in said one end of the rivet engaging member, a spring means for holding the peen socketed in said pocket, a bracket slidably connected to the riveting means having one end pivotally connected to said pivot point of the rivet engaging member to effect angular displacement of said member relative to the peen upon longitudinal movement of the bracket relative to the riveting means.

4. A peening attachment for rivet guns having a housing and a bore formed therein for receiving the shank of a riveting peen, said attachment comprising a sleeve adapted to loosely surround the housing, an arm rigidly connecting with said sleeve and adapted to project beyond the end of said housing and generally parallel to the axis thereof, a rivet engaging member swingably car-

ried by the outer end of said arm and extending laterally therefrom, a force transmitting member having one end thereof connecting with the free end of said rivet engaging member by means of a ball and socket joint and having its other end formed to provide a shank adapted to be received in said bore for transmitting a riveting force to said rivet engaging member, said rivet engaging member being angularly movable with respect to said force transmitting member by axial movement of said arm and sleeve.
